CAR TRUCK

Claude L. Orr, Columbus, Ohio, assignor to The
Buckeye Steel Castings Company, Columbus,
Ohio

Application December 5, 1938, Serial No. 244,095

11 Claims. (Cl. 105—221)

This invention relates to improvements in means for applying, shimming and retaining journal boxes in the side frame pedestal openings of railway car trucks.

5 The main object of the invention is to provide a simple and economical means for applying, shimming and retaining either roller bearing or plain bearing journal boxes in side frame pedestal openings.

10 With the foregoing object outlined, and with other objects in view, which will appear as the description proceeds, the invention consists in the novel features hereinafter described in detail, illustrated in the accompanying drawings and more particularly pointed out in the appended claims.

In the drawings:

Fig. 1 is a side elevation of a portion of a car truck side frame and journal box in accordance 20 with the invention, and with the shim omitted but with my improved journal box retaining means shown.

Fig. 2 is a transverse sectional view taken on the line 2—2 of Fig. 1, but with the journal box 25 in elevation.

Fig. 3 is a view similar to Fig. 1 but showing a relatively thin shim in use, and with the journal box retaining plate in an inverted position relatively to the position shown in Fig. 1.

30 Fig. 3a is a view like a portion of Fig. 3 but showing a thicker shim in use.

Fig. 4 is a transverse vertical sectional view taken on the line 4—4 of Fig. 3 and showing the journal box in elevation.

35 Figs. 5 and 6 are plan and side elevations respectively of the thin shim.

Figs. 7 and 8 are similar views of the thicker shim.

Fig. 9 is a top plan view of the retaining plate.

40 Referring first to Figs. 1 and 2 which are views of a frame pedestal opening with the journal box applied, it will be noted that there are no shims at the top of the box. In such unshimmed application of the invention, the pedestal opening is provided with four accurately spaced depending lugs 1 which embrace the corner portions of an upstanding lug 2 arranged at the top of the journal box 3. The contact at the vertical faces of lugs 1 and 2 serves to properly space the journal box 3 in a longitudinal direction in the frame pedestal opening 4, and it will be observed that clearances 5 are shown between the sides of the journal box and the vertical faces of the pedestal opening, indicating that contact between the box and frame along these lines is not depended on

to space the journal box longitudinally. The clearances 5 are exaggerated on the drawings for the purpose of clearness.

The journal box is held in the frame opening in a transverse direction by means of upstanding flanges 6 on the top of the box which embrace the side frame at the top of the pedestal opening; and by flanges 7 at the sides of the box which embrace the side frame columns 8.

While the journal box may be retained in the 10 pedestal opening in a vertical direction by any suitable means, I prefer to employ the special means which I have devised. It comprises an L-shaped or substantially angular retaining plate 9, the head of which is provided with a 15 horizontal surface 9a adapted to contact the lower ends of the column flanges 7 at one side of the journal box. When the top of the box is in contact with the top of the pedestal opening, there is a small clearance 10 between the co- 20 operating faces of the retaining plate and the column flanges in order that the retaining plate may be moved easily.

The plate, as best shown in Fig. 9, is provided with a narrow shank 9b which is inserted in an 25 opening provided in one of the side frame pedestal columns, and which is formed partially by tie bar 9x of the side frame. Adjacent to the tie bar, the side frame is provided with a substantially angular recess 11 which allows the head of 30 the retaining plate 9 to clear the flanges 7 when the shank of the plate is pushed toward the tie bar 9x. A rounded corner 9c is provided on the head of the retaining plate to fit a rounded fillet 11a of the side frame when the retaining plate is 35 fully retracted.

After the journal box is applied to the frame, and the retaining plate is projected to a proper position to underlie the flanges 7 at one side of the journal box, the plate is secured in position 40 by any suitable means such as bolts 12. An upper tie 15 is provided between the side walls of the frame just above the tail end of the shank of the plate and it cooperates with the tie 9x 45 to guide the shank in its sliding movements. If, for any reason, the weight of the journal 3 is supported by the retaining plate at surface 9a, the upward vertical thrust at the inner end of the shank of the retaining plate is resisted partly 50 by the tie 15 and partly by the bolts 12. In the absence of tie 15, bolts 12 would have to resist all of this upward thrust and there would be a greater tendency to loosen them. Tie 15 also serves as a stop for the angular heads of bolts 55

12, preventing them from rotating when the nuts are applied.

When a shim is not employed, it will be observed that a portion of the head projects above the shank of the plate 9 but as may be seen from Fig. 3, when a shim is used, the retaining plate is inverted to accommodate the lowered position of the flanges 7.

- Referring now to the shimmed construction, illustrated in Figs. 3, 4, 5 and 6, a shim 13 may be used when its thickness 13a is less than the vertical height of the lugs 1 of the frame. Lugs 13b at opposite ends of the shim fit between the lugs 1 at the opposite sides of the pedestal opening. 15 The flanges 6 of the journal box embrace the shim transversely thereby spacing the top of the box transversely. Since the thickness of the shim is less than the vertical height of the lugs 1, the latter extend below the shim as shown at X in 20 Fig. 4 and embrace the upstanding portion 2 of the journal box, thereby spacing the box longitudinally in the same manner as when the shim was not applied.

Shim 14 (Figs. 3a, 7 and 8) is to be used when its thickness 14a is greater than the vertical height of lugs 1. Since the lugs 1 will not, in this case, embrace portion 2 of the box, vertical depending lugs 14b are provided at the opposite ends of the shim, and these lugs embrace portion 2 of the journal box while the surfaces 14c of the shim are embraced by the lugs 1 thereby spacing the journal box longitudinally in the pedestal opening. Transversely, the lugs 14b fit between the lugs 1, and flanges 6 of the journal box embrace the shim thereby spacing the top of the box in the frame opening.

As before stated, when either shim is used, the retaining plate must be removed and reapplied in an inverted position. It is so designed that when applied upside-down, sufficient clearance is provided between it and the column flanges of the box to allow shims of nominal thickness to be used. It will also be noted that whether the retaining plate is right-side-up or up-side-down, in case bolts 12 should be loosened and lost during service, the journal box will act as an abutment and prevent the shank of the plate from moving out of the opening in the side frame, and thereby prevent loss of the plate.

Many modifications of the invention will be apparent to those skilled in the art, without departing therefrom, or from the scope of the claims, and since the foregoing disclosure has been given by way of example for clearness and understanding, no unnecessary limitations should be understood and the appended claims should be construed as broadly as the state of the art permits.

What I claim and desire to secure by Letters Patent is:

1. In a railway car truck, a side frame member having a pedestal opening and provided at the top of the opening with oppositely disposed pairs of depending spaced lugs, a journal box extending into said opening, and means at the top of the box having opposite ends abutting against said lugs, said means comprising a shim interlocked with the journal box and of a height at least equal to the height of the lugs.
2. In a railway car truck, a side frame member having a pedestal opening and provided at the top of the opening with oppositely disposed pairs of depending spaced lugs, a journal box extending into said opening, and means at the top of the box having opposite ends abutting against

said lugs, said means comprising a shim having corner recesses to receive said lugs and provided with depending lugs embracing the upper portion of the journal box.

3. In a railway car truck, a side frame member having a pedestal opening and provided at the top of the opening with oppositely disposed pairs of depending spaced lugs, a journal box extending into said opening, shim means at the top of the box having opposite ends abutting against said lugs, and upstanding flanges at the top of the journal box engaging the shim means to prevent transverse movement of the side frame member and journal box relatively to one another.

4. In a railway car truck, a side frame member having pedestal columns arranged at opposite sides of a pedestal opening, a journal box extending into said opening, an invertible substantially L-shaped retaining plate for the journal box arranged at the lower end of one of said columns, and means detachably securing the retaining plate to the side frame member, the retaining plate having a head, and the side frame member having a recess to receive said head when the retaining plate is in retracted position to prevent the head from obstructing the removal of the journal box.

5. In a railway car truck, a side frame member having a pedestal opening with columns arranged at opposite sides thereof, a journal box extending into said opening and provided at one side with flanges which cooperate with one of the columns to limit relative movement of the journal box and side frame member transversely of the truck, the side frame member having a retaining plate recess and supporting means adjacent the lower ends of said flanges, a retaining plate extending into said recess and having a portion arranged below said flanges and forming an abutment for the flanges, another portion of the retaining plate resting on said supporting means, a tie within the side frame member immediately above a portion of said plate, and a bolt securing the retaining plate to said supporting means and having an angular head abutting against said tie and prevented from turning thereby.

6. In a railway car truck, a side frame member having a pedestal opening with columns arranged at opposite sides thereof, a journal box extending into said opening and provided at one side with flanges which cooperate with one of the columns to limit relative movement of the journal box and side frame member transversely of the truck, the side frame member having a retaining plate recess and supporting means adjacent the lower ends of said flanges, a substantially L-shaped retaining plate extending into said recess and having a head portion arranged below said flanges and forming an abutment for the flanges, another portion of the retaining plate forming a narrow shank resting on said supporting means, a tie within the side frame member immediately above the shank portion of said plate, and a bolt securing the retaining plate to said supporting means and having an angular head abutting against said tie and prevented from turning thereby.

7. In a railway car truck of the type having a side frame provided with pedestal columns arranged at opposite sides of a pedestal opening, and a journal box extending into said opening and arranged for shim means at its top to raise said frame relative to said box, the improvement which comprises an invertible retaining plate

slidably arranged at the lower end of one of said pedestal columns for movement toward and away from said opening, said plate being adapted to retain the journal box in one position when the latter is shimmed, the plate comprising a substantially vertically extending lug that is adapted when the plate is inverted to retain the journal box when the latter and side frame are not shimmed, the last-mentioned pedestal column being shaped to receive the lug when the latter is in retracted position.

8. In a railway car truck, a side frame member having a pedestal opening and provided at the top of the opening with oppositely disposed pairs of depending spaced lugs, a journal box extending into said opening and having vertical flanges which extend upwardly from the top thereof, and means at the top of the box having opposite ends abutting against said lugs, said means including a shim arranged between the top of the box and the side frame member, the upper edges of said flanges being arranged below the upper surface of the shim.

9. In a railway car truck, a side frame member having a pedestal opening and provided at the top of the opening with oppositely disposed pairs of depending spaced lugs, a journal box extending into said opening and having vertical flanges which extend upwardly from the top thereof, and means at the top of the box having opposite ends abutting against said lugs, said means including a shim arranged between the top of the box and the side frame member, the upper edges of said flanges being arranged below the upper surface of the shim, said shim being of less height

than said lugs and being interlocked with the lugs and flanges.

10. In a railway car truck, a side frame member having a pedestal opening and provided at the top of the opening with oppositely disposed pairs of depending spaced lugs, a journal box extending into said opening and having vertical flanges which extend upwardly from the top thereof, and means at the top of the box having opposite ends abutting against said lugs, said means including a shim arranged between the top of the box and the side frame member, the upper edges of said flanges being arranged below the upper surface of the shim, the shim having recessed corners into which said lugs extend.

11. In a railway car truck of the type having a side frame provided with pedestal columns arranged at opposite sides of a pedestal opening, and a journal box extending into said opening and arranged for shim means at its top to raise said frame relative to said box, the improvement which comprises an invertible substantially L-shaped retaining plate slidably arranged at the lower end of one of said pedestal columns for movement toward and away from said opening, said plate being adapted to retain the journal box in one position when the latter is shimmed, the plate comprising a head that is adapted when the plate is inverted to retain the journal box when the latter and side frame are not shimmed, the last-mentioned pedestal column having a rabbet adapted to receive the head when the retaining plate is in retracted position.

CLAUDE L. ORR. 35
